UNITED STATES PATENT OFFICE.

ANDERS PONTEN, OF BERKELEY, CALIFORNIA, ASSIGNOR OF FORTY-FIVE ONE-HUNDREDTHS TO JAMES D. MILLAR, OF PORTLAND, OREGON.

CENTRIFUGAL SLUICING-MACHINE.

980,001.

Specification of Letters Patent. Patented Dec. 27, 1910.

Application filed September 27, 1906. Serial No. 336,481.

To all whom it may concern:

Be it known that I, ANDERS PONTEN, a citizen of the United States, residing at Berkeley, in the county of Alameda and State of California, have invented certain new and useful Improvements in Centrifugal Sluicing-Machines, of which the following is a specification.

This invention relates to the separation of metallic particles especially gold from sand or gangue and to the process commonly called concentration, also relates to that class of machines that employ centrifugal force in such separation or concentration, and to certain useful improvements in such process and apparatus.

My improvements consist in the application to the material, of centrifugal force in two planes directed, to separating and forming into strata the mineral particles and sand according to their respective gravity, and also in a lesser degree to causing by means of surfaces oblique to the axis of rotation a slow flow of the material approximately transverse to the direction of the centrifugal force, thereby causing the deposited or compressed strata to move one upon the other so the lighter material will be pushed off leaving an accretion of the mineral particles to a depth governed by peculiarly constructed dams, or riffles, that oppose but do not arrest the flow of the lighter materials.

The objects of my invention are to attain celerity and at the same time a uniform action of centrifugal force on the moving material irrespective of accumulated and arrested strata of the mineral and to attain by means of varying the velocity of rotation, different degrees or relation between the centrifugal forces acting for selection or separation and for the off-flow of the gangue or waste sand.

As the separation of mineral particles or the concentration of ores by mechanical apparatus depends upon the relative weight of the substances dealt with, it was natural and common to depend upon gravity in connection with agitation to cause such separation, but gravity being a limited force, especially in dealing with small particles where their surface far exceeds in proportion their mass, the application of centrifugal force by reason of its greater and controllable intensity has been substituted for gravity in a great

number of cases and has with certain limitation performed separation but failed to divide or select the mineral particles from the gangue in a way to permit uniform and successful continuous treatment. The reason for such failure is that the centrifugal force has been applied normally to and not obliquely on the accumulating strata, and mainly because the catch surfaces or riffles have been so made as to arrest positively at certain depths the flow of the waste material, thus setting up not only a limitation to continuous action, but continually varying conditions of treatment as the process went on.

In my invention the centrifugal force is divided by employing a conical or divergent rotary vessel containing or receiving the material while in rapid revolution, the angle or slope of the inner acting surfaces being such as to apply about nine-tenths of the centrifugal force normal to the strata of the material and about one-tenth to longitudinal flow thereof and in combination with this dual force obstructing riffles with their faces at an angle of or approximately of forty-five degrees to the axis of rotation, so arranged respectively that at some predetermined speed of revolution and degree of centrifugal force the outer or denser mineral stratum will pass under, continue to form and raise and discharge the gangue over the riffles because of their faces being oblique to the longitudinal flow. This angle has been tentatively ascertained and as before remarked is contingent on speed of revolution or the relative degrees of centrifugal force acting transversely and longitudinally on the stratum of material, the angles, of the respective surfaces and to some extent the nature of the material being treated.

Apparatus employed in applying my invention is illustrated by the drawings that accompany and form part of this specification, Figure 1 being a vertical section through a machine or apparatus constructed for that purpose, Fig. 2 a horizontal section on the line 1—1, in Fig. 1, and Fig. 3 a diagram to illustrate the effect upon and disposition of the material when dually acted upon by centrifugal force according to my invention.

A, represents the rotary chamber or circulator which it will hereafter be termed.

This circulator is attached to a suspended driving shaft 2. At the bottom of the circulator A is located a helical feeder 3, similar in many respects to a four blade propeller. At the top of the circulator are the removable radial arms 4, 4, extending from the hub 5 for holding the circulator A concentric with the shaft 2. On the inside of the circulator A are a number of annular ridges or riffles 6, between which are spaces or zones constituting open and unobstructed separating surfaces. The lower surfaces of these ridges or riffles are obtuse to the adjacent wall of the chamber or at an angle of about 45° to the axis of rotation of the chamber.

Surrounding the circulator A is a stationary annular casing 8 which at the bottom has a removable cup 9 provided with a receiving hopper 10 and inlet tube 11 leading from the bottom of the hopper into the bottom of the cup. At the upper end of the casing 8 is an annular trough 13, the bottom 14 of which has a helical form, for facilitating an easy flow of tailings and water to the discharge spout 15. A loose annular flange or cover 16 is placed on top of the casing 8 so that it partially closes the trough 13.

30 Bearings 17, 17, are provided for the upper end of the shaft 2, which at this point is provided with a pulley 19 by means of which and the belt 20 motion is transmitted to the machine from a suitable motor, (not shown).

35 The numeral 21 indicates a movable receptacle for water and solids, it being preferably located on a truck 30 of any approved form. In this movable receptacle 21 the dotted line 22 indicates the surface of the water and the numerous dots 23 the solid matter on the bottom of the receptacle. A spout 25 conveys water from the tank or receptacle 21 into the receiving hopper 10 and numeral 26 stands for an adjustable 40 overflow pipe of any suitable construction—(or as shown)—held by friction only in the side of tank 21 allowing the inner end to be turned to any angle required for regulating the height of the water surface 22, in the 45 tank or receptacle 21. A bucket 27 receives the overflow water from the tank or receptacle.

50 Numeral 28 shows a part of a spout from a hopper, from which the solid matters or 55 gangues are fed into the receiving hopper 10.

Referring to Fig. 3 this will best serve to explain the process. The angle B is a resultant of the angle C, the latter being as before explained so arranged as to direct about one-tenth of the centrifugal force vertically or parallel to the axis of rotation. The face angle of the riffles 6, or the angle B is at or approximately at 45° to the axis of rotation and is at an obtuse angle to the wall of 60 chamber A, so the lighter materials slide

over this face when aided by the lifting action of the heavier stratum 7^a of mineral so the process can go on under practically uniform conditions until the charge at 7^a nears the top of the riffles 6. The dotted lines 7^b 70 shows the accumulation of solids under the riffle, and 7^a, the lower edge as far down as they will accumulate according to the physical law for the angle of repose. Inside the dotted line 7^b and below 7^a everything is 75 moving in the direction of the arrow. The space from D to E between the riffles 6 is necessary to afford the space required for separation as will be understood, such space may be made more or less, but experiments 80 thus far point to an arrangement practically as shown in the drawings, in which the distance between riffles is at least three times the length of the space occupied by the accumulated solids beneath the riffle. 85

When the machine is ready for operation, the tank 21 is filled with water in sufficient quantity for some of it to flow through spout 25 and partially fill the receiving hopper 10 and bottom cup 9 as indicated by dotted 90 lines 12. The machine is then set in rapid motion and when full speed is attained, the helical feeder 3 sucks the water up into the circulator A, where it travels upward along the inner wall of the latter until it reaches 95 the top at which point the water is discharged into the annular trough 13 and thence through spout 15, the water is returned to the tank 21. As soon as the circulation of the water is in running order, as 100 above stated, the supply of gangue or black sand is introduced from spout 28. Dropping into the hopper 10, this gangue or black sand mixes with the water and after that the gangue follows the course of travel of the 105 water through the machine, as above described and indicated by arrows in the drawing. From the moment the gangue enters the circulator A through the feeder 3, it is subjected to the action of centrifugal force, 110 created by the high rotary velocity of the circulator A and as it travels upward along the inner conical surface of the circulator, it is distributed and moves in a uniform layer over the surface or zone between the riffles, 115 the heavier particles lodging against the said riffles as indicated by the lines 7 leading down only to such extent as the physical law for the angle of repose will permit.

The specific gravity of gold being six 120 times that of auriferous gangue and nineteen times the specific gravity of water causes the gold subject to the action of centrifugal force, during its course of travel over the open conical surface or zone formed 125 between a riffle ring 6, and the layer of solids 7, held under the next riffle above, to instantly separate and lodge nearest the inner wall surface of the circulator A, which surface it follows until it reaches the layer of 130

- solids located under the nearest riffle ring above. Upon reaching that layer of solids the gold by virtue of its greater specific gravity continues its travel along the wall 5 surface and gradually crowds out the other solids, the gold itself remaining under the riffle until the machine is stopped for a cleanup the separating of gold from gangue by passing the material over open or unobstructed zones of a conical surface while subjected to the action of centrifugal force being an important feature of my invention. After the solids or tailings pass the top riffle they are discharged into the annular trough 13 and pass out of the machine together with the water through spout 15, dropping to the bottom of tank 21, while the water through spout 25 continues on its course through the machine 10 indefinitely, this being another feature of my invention, namely to economize in the use of water by constantly circulating and re-circulating only the water originally contained in the machine when started. As the tailings 23 accumulate in tank 21 they gradually displace the water, originally filling the tank, but in order to maintain a constant, uniform head of water in the tank 21, the adjustable overflow pipe 26 is employed 15 for letting out displaced water which is saved in a bucket 27. When the tank 21 is filled with tailings it is replaced by another similar one and the operation is continued until the accumulation of gold under the riffle rings necessitates stopping and cleaning out the separated gold. The clean-up is accomplished by washing the contents under the riffles 6 down into the bottom cup 9, which afterward is removed and emptied 20 into some other receptacle. In this way by a most economical use of water I am enabled to separate gold from auriferous gangue or black sand while subjected to centrifugal action by passing the material over free and unobstructed surfaces in a rapidly revolving conical circulator, provided with rings or riffles at such a distance apart that the greater part of the surface between adjoining rings or riffles is left clear after the solids 25 have accumulated below a riffle to its fullest extent according to the physical law for the angle of repose.
- More or less slight changes might, of course, be made in the form and arrangement of the several parts described without departure from the spirit and scope of my invention, and hence I do not wish to limit myself to the exact construction or method herein set forth, but:—
- Having fully described my invention, what I claim as new and desire to secure by Letters Patent, is:—
1. A centrifugal sluicing machine comprising a rotary circulator, a casing surrounding the circulator, and a removable cup at the bottom of the casing in which the concentrates are finally washed and caught after the completion of the sluicing operation.
2. A centrifugal sluicing machine comprising a rotary circulator, a casing surrounding the circulator, a removable cup at the bottom of the casing, a receiving hopper in communication with the cup, a trough at the upper end of the casing and means for rapidly revolving the circulator.
3. A centrifugal sluicing machine comprising a rotary circulator, a casing surrounding the circulator, a removable cup at the bottom of the casing, a receiving hopper in communication with the cup, a trough at the upper end of the casing and means for automatically circulating and re-circulating the water used in the operation of the machine.
4. A centrifugal sluicing machine comprising a rotary circulator, a casing surrounding the circulator, a removable cup at the bottom of the casing for removing the concentrates, a receiving hopper in communication with the cup, a trough at the upper end of the casing and means for automatically circulating and re-circulating the water used in the operation of the machine, said means comprising a tank which receives the discharge from the trough at the upper end of the casing, said tank having means whereby it discharges into the cup at the bottom of the casing and means for catching any overflow from the tank.
5. A centrifugal sluicing machine comprising a rotary circulator, a surrounding casing having a removable cup at the bottom and a trough at the top thereof, said trough having a helical bottom and the lower end of the circulator having a helical feeder.
6. A centrifugal sluicing machine comprising a rotary circulator, a surrounding casing having a removable cup at the bottom and a trough at the top thereof, said trough having a helical bottom and the lower end of the circulator having a helical feeder, and means for automatically returning the water discharged from the trough to the cup for re-circulation through the machine.
7. In a centrifugal sluicing machine, the combination with an outer casing, and a rotary circulator having overhanging annular rings or riffles beneath which the concentrates are caught, the working faces of which riffles are at an angle of or approximately of 45° to the axis of rotation of the circulator of a combined cup, hopper and inlet tube removably secured to the lower end of the casing.
8. In a centrifugal sluicing machine, a conical rotary circulator, annular rings or riffles on the inner walls thereof, the lower

faces of which are at an obtuse angle to said walls, a casing inclosing the circulator, and a removable cup at the bottom of the casing.

9. In a centrifugal sluicing machine, a 5 conical rotary circulator, annular rings or riffles on the inner walls thereof, the lower faces of which are at an obtuse angle to said walls, a helical feeder at one end of said circulator, a casing surrounding the latter,

and a removable cup at the bottom of the 10 casing.

In testimony whereof I have signed my name to this specification in the presence of two subscribing witnesses.

ANDERS PONTEN.
